(57) **CLAIM**

The ornamental design for a vehicle antenna adapter, as shown and described.

DESCRIPTION

FIG. 1 is a first perspective view of the vehicle antenna adapter;

FIG. 2 is a second perspective view of the vehicle antenna adapter;

FIG. 3 is a front view of the vehicle antenna adapter;

FIG. 4 is a rear view of the vehicle antenna adapter;

FIG. 5 is a right side view of the vehicle antenna adapter;

FIG. 6 is a left side view of the vehicle antenna adapter;

FIG. 7 is a top view of the vehicle antenna adapter; and,

FIG. 8 is a bottom view of the vehicle antenna adapter.

The broken lines show portions of the vehicle antenna adapter that form no part of the claimed design.

Additionally, the dot shading is included to illustrate surface contours and not color; the shading is not a feature of the claimed design.
